PREPARING OPEN AND CLOSED HOLLOW
BODIES BY CENTRIFUGAL CASTING

Willibald Raym, Deuz, Karl Mertens, Klaefeld, and
Albert Sälzer, Geisweid, Germany, assignors to
Hundt & Weber Gesellschaft mit beschränkter
Haftung, Geisweid, Germany, a Corporation

Application January 5, 1931, Serial No. 506,766,
and in Germany August 1, 1929

2 Claims. (Cl. 22—65)

It has already been proposed to prepare cylindrical rings by centrifugal casting, by providing a guide wall in the rotary mould for the liquid material which rises from the bottom of the mould. This arrangement however permits only of casting cylindrical rings open at both ends, which rings are then further worked by rolling and like operations. With such an arrangement it is not possible to prepare, by centrifugal casting, hollow bodies which are closed at one or both ends nor hollow bodies which have a plurality of walls.

The apparatus according to the present invention permits of the preparation of such hollow bodies in that a series of cores are disposed in the centrifugal casting mould which so guide the metal that the said hollow bodies are obtained. At the same time provision is made for retaining the cores in position.

20 The arrangement may be such that the cores, or the mould closure plate carrying the cores, are movable relatively to the mould both to permit of the closure of one side of the hollow body by the metal and also to prevent a premature solidification of the material with consequent incomplete filling of the mould in the casting more particularly of thin walled hollow bodies.

Also the casting gutter may be made movable and may be introduced into the rotary mould prior to, simultaneously with, or subsequent to the core, in order to ensure a uniform distribution of the material and a complete filling of the mould. In certain circumstances two movable casting gutters may be used which execute different motions or are moved differently with respect to each other, or a single gutter with two outlets may be utilized and in this case the outlets may be provided with obturating devices to permit of rendering them temporarily inoperative.

With such an arrangement it is possible to cast by the centrifugal method the comparatively thin walled tuyères of copper or bronze for blast furnaces.

The arrangement may also be such that it is possible to cast simultaneously or in succession in two hollow moulds which are mounted to be tiltable about a common shaft on a suitable frame, so as to permit of casting both in a horizontal and also in a vertical position. The shaft about which tilting occurs serves at the same time as driving shaft and preferably a friction gearing is provided in order to permit of varying the speed within certain limits. The

transmission to the two axles carrying the moulds is effected by means of a friction gearing with conical friction wheels which is so disposed that each mould may be individually disengaged from the driving shaft by displacement 60 of a conical friction wheel in order that one mould may be prepared while casting is taking place in the other. Appropriate brake devices are provided to bring the mould disengaged from the driving shaft to rest in the shortest 65 possible time.

In order to effect acceleration in comparatively short time, of the material, a cone may be provided at the bottom of the mould which cone urges the material along with it in its rotation 70 and throws it outwardly. If desired the surface of the cone may be provided with turbine or scoop like ridges or grooves.

Various embodiments of the invention are shown by way of example in the accompanying 75 drawings, in which:

Fig. 1 shows in longitudinal section a mould with core, core support and casting gutter as used for preparing an open multiple-walled hollow body,

Figs. 1a and 1b are enlarged views of the core carrying bolts.

Fig. 2 is a corresponding end elevation view.

Fig. 3 shows a specific construction of the core support in longitudinal section.

Fig. 4 is a corresponding view of a different construction of core support.

Fig. 5 shows a mould and core for the preparation of a closed single-walled hollow body.

Fig. 6 shows mould and core for the preparation of a closed multiple-walled hollow body.

Fig. 7 shows mould and core for the preparation of a closed multiple-walled hollow body of different form.

Fig. 8 shows mould and core for the manufacture of a hollow body having two cavities.

Fig. 9 shows a second constructional form for the manufacture of said hollow body.

Fig. 10 shows a section through a tuyère for blast furnaces, such as can be made with the apparatus according to the present application,

Figs. 11 and 12 show an arrangement which is particularly suitable for carrying out the present process and in particular

Fig. 11 is a plan view, partly in section,

Fig. 12 shows an elevational view,

The mould 2 which is rotatable about the axle 3 is used for preparing an open, multiple-walled hollow body such as is indicated by the reference numeral 1 in Fig. 1. The axle 3 may be dis-

posed horizontally, as shown, but may be journaled vertically, and is driven at appropriate speed of rotation.

The open end of the mould is closed by a plate 5 4 which is secured to the mould by bolts 5 provided along its periphery. The plate is provided with a central aperture 6 through which the casting gutter 7 is introduced.

A number of bolt shaped core supports 8 are 10 secured to the plate 4 and the core 9 is formed about them in clay or other suitable material. The core carrying bolts 8 are preferably furnished with a bore 10 through which the gases occurring when the material of the core is heated can escape. In the case of completely closed hollow bodies this bore may serve for the removal of material of the core by means of compressed air or water after the hollow body has been completed, whereupon the cast-in core carriers 15 are closed by plugging.

The core carrier 8 may of course be constructed without a bore. Preferably and as shown at 20 8, it is constructed as a cone or pyramid, but it may be cylindrical as shown at 8', with a flange 11 at its end.

The plate 4 carrying the core carriers 8 or 25 8' is provided with a large number of apertures 12 as shown more particularly in Fig. 2 in order to permit of disposing the different core carriers 30 in any desired relative positions as required. The apertures may be temporarily closed by screwed plugs to prevent the liquid metal from flowing out of the mould through them. The holes 13 at the periphery serve to receive the bolts 5 by means of which the plate is secured to the mould.

If during simultaneous rotation of the mould 35 2 about the shaft 3, liquid metal is cast in through the casting gutter 7 then in the first 40 place the outer wall of the hollow body is prepared and then the inner wall. The various methods of casting in the metal will be discussed in detail later.

Instead of core carriers 8 and 8' as shown in 45 Figs. 1 and 2, core carriers having uninterrupted walls as shown in Figs. 3 and 4, may be used. These core carriers consist for example of a hollow cylinder 14, such as a sheet steel cylinder, which at its innermost end is provided with an outwardly extending flange 15. The core 50 16 of clay or the like is formed on the outside of the cylinder. The core carrier plate is secured by the bolts 17.

In the embodiment according to Fig. 4 the 55 core material 16 is on the inner wall of the cylindrical core carrier 14. In this embodiment this core carrier is integral with the core carrier plate 4.

In some circumstances it is of course possible 60 to use a complete metal core without clay.

In Figs. 5-9 are shown various moulds with cores and core carriers for the preparation of the most diverse hollow bodies. In the construction according to Fig. 5 a single core 24 65 is suspended on core carriers 8 in the hollow mould 2 provided with core carrier plate 4. Then by casting in the material a completely closed hollow body is formed. Then as already 70 mentioned the core can be blown or washed out through the apertures in the core carriers 8 whereupon the apertures in these cases in the core carriers are closed by the plugs. In the embodiment shown in Fig. 6 a closed multiple-walled hollow body is prepared in that a solid 75

core 25 is centrally arranged and an annular core 26 is disposed about it. These cores also are connected to the core carrier plate 4 by means of core carriers 8.

In the construction according to Fig. 7 a similar arrangement is provided but the annular core 26 of Fig. 6 is replaced by a cup-shaped core 27.

In the embodiment according to Fig. 8 two solid cores 28 and 29 are arranged one above the other and they are both carried by core carriers 8 which are secured to the core carrier plate 4. In this arrangement the core carriers for the lower core 29 must pass through the upper core.

The constructional form shown in Fig. 9 permits of the preparation of the same hollow body as that according to Fig. 8 but the lower core is carried by the core carriers 8' from below, these carriers being secured to the mould.

The apparatus shown in Figs. 11 and 12 comprises a support 32 on which is disposed a frame 34 adapted to pivot about 33 the two discs 35 being rotatably journaled on shafts 36 on the member 34. The moulds 37 are secured in known manner on these discs 35. Each shaft 100 36 carries a conically shaped friction wheel 38 and this friction wheel is connected with the driving wheel 40 by way of the conical friction wheel 39. The shaft 41 of this driving wheel is provided with a friction disc 42 which contacts 105 with the friction wheel 43 carried on the shaft 44 and displaceable thereon by means of a screw 45 and a hand wheel 46. The shaft 44 is driven from any suitable motor by means of pulley 47 but this belt transmission can be replaced by a 110 bevel gear or any other transmission. If desired a change speed gear or an intermediate gearing may be interposed between the motor and the shaft 44.

The conical friction wheels 39 are adapted to 115 be axially displaced by means of hand wheels 48 and in this way any wear of the friction wheels 38, 40 can be compensated and also the requisite pressure between the different friction wheels can be obtained. Furthermore by completely withdrawing one or other friction wheel 39 the corresponding disc 35 with the associated mould 37 can be disconnected from the motion, the brake levers 49 acting on the friction wheels 38 being used in order to bring the mould in 125 question to rest as rapidly as possible.

The pivotation of the entire frame 34 together with the moulds 37 and the corresponding gearing is effected about the pins 33 mounted on the frame 34 and adapted to turn in the bearings 50. A clamping device 51 may be provided on one or both bearings in order to be able to secure the entire frame in any desired position, more particularly in horizontal and vertical 130 position.

The pivotation may be effected either manually by means of a suitable lever or by gear wheel or pivotation gear or a separate motor may be used for the pivotation. In certain circumstances the pivotation may be derived from a separate gear directly connected with the main drive.

When the shaft 44 and with it the friction wheel 43 are set in rotation by means of the pulley 47, the friction disc 42 together with the shaft 41 and the conical friction wheel 40 are rotated and with greater or less speed according to the position of the friction wheel 43 with respect to the disc 42. The rotary motion is 145 150

transmitted by way of the friction wheels 39 to the two friction wheels 38 and thus to the shafts 36 and the discs 35 carrying the moulds 37.

Preferably one of the friction wheels 39 is displaced outwardly so that only one mould is driven and casting is effected in this mould by the centrifugal process. The idle mould is in the meantime prepared anew. Then this mould is thrown into gear and the other disconnected, the further rotation of the latter being stopped by the corresponding brake 49. Naturally it is possible to use both moulds for casting simultaneously if desired.

According to the setting of the frame 34 casting may be effected in horizontal, vertical or in oblique position.

Preferably a cooling device for the moulds is also incorporated in the form of tubes 52 passing through the pivot pins 33 to convey a cooling liquid or other cooling medium to the moulds. In this way a very rapid succession of casting operations is made possible.

The friction gearing described may if desired be replaced by any other suitable gear such as toothed gearing or the like. Hollow bodies of

every kind for example blast furnace fittings, blast and slag tuyères, cooling boxes, cooling rings as well as axle bearings or brasses, cylinders, containers of all kinds can be cast by the process described above and with the apparatus described for carrying out the process.

We claim:

1. In a centrifugal casting apparatus in combination, a rotatable mould open at one end, means for mounting a core carrying plate on the open end of said mould, said plate having a large central opening and a plurality of smaller openings therein, means projecting from the cores for mounting the latter on said plate, said cores adapted to form a plurality of cavities in said casting.

2. In a centrifugal casting apparatus as defined by claim 1 in which the said means for mounting said core on said carrier plate are provided with openings for removing the core from the finished casting.

WILLIBALD RAYM.
